US0D1111769S

(12) **United States Design Patent** (10) **Patent No.:** **US D1,111,769 S**
(45) **Date of Patent:** **** Feb. 10, 2026**

(54) **LATCH**

(71) Applicant: **SHENZHEN YANGNING AUTO ACCESSORY CO., LTD**, Shenzhen (CN)

(72) Inventor: **Shiawdar Shaun Yue**, Shenzhen (CN)

(73) Assignee: **SHENZHEN YANGNING AUTO ACCESSORY CO., LTD**, Shenzhen (CN)

(**) Term: **15 Years**

(21) Appl. No.: **29/940,026**

(22) Filed: **Apr. 30, 2024**

(30) **Foreign Application Priority Data**

Apr. 7, 2024 (CN) 202430186376.0

(51) **LOC (15) Cl.** **08-07**

(52) **U.S. Cl.**

USPC **D8/336**

(58) **Field of Classification Search**

USPC D8/300, 301, 307, 308, 330, 331, 336,

D8/338, 382, 394, 400

CPC E05C 19/14; E05C 1/14; B25B 5/12

See application file for complete search history.

(57) **CLAIM**

The ornamental design for a latch as shown and described.

DESCRIPTION

FIG. 1 is a perspective view of a latch showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded perspective view thereof.

The broken lines in the drawings depict portions of the latch that form no part of the claimed design.

1 Claim, 9 Drawing Sheets
